UNITED STATES PATENT OFFICE.

THEODORE BERGNER, OF PHILADELPHIA, PENNSYLVANIA.

MACHINE FOR MAKING ENVELOPES.

Specification forming part of Letters Patent No. 16,576, dated February 10, 1857.

To all whom it may concern:

Be it known that I, THEODORE BERGNER, of the city of Philadelphia and State of Pennsylvania, have invented a new and Improved Envelope-Folding Machine; and I do hereby declare that the following is a full, clear, and exact description of the construction and operation of the same, reference being had to the accompanying drawings, making part of this specification, and in which the same letters of reference allude to similar parts throughout the several views.

Figure 1 is a front elevation of my improved envelope-machine, with part of it shown in section. Fig. 2 is a sectional side view of the machine. Fig. 3 is a sectional plan on the line 1 2, Fig. 1. Fig. 4 shows the blank of an envelope while undergoing the process of stamping and pasting. Fig. 5 is a detached sectional view of the folding apparatus. Fig. 6 is a detached sectional view of the folder on an enlarged scale.

A and A' are the two frames or standards of the machine, supporting the table B, on which is again secured the frame C. This frame has projections *a a* and *b b* on its front, forming V-shaped guides for the sliding rod D. The link E, which at one end connects to rod D by means of a stud *c*, is at its other end attached to the lever F, which has its fulcrum on the pin *d*, (bolted to a projection of frame C,) and which gives a downward motion to the sliding rod D by means of rod G, this rod being at its lower end acted upon by cam H on the main shaft I.

e is the guide for rod G, which at its lower end is provided with the roller *f* to facilitate the action of cam H.

The main shaft I revolves in the direction of its arrow, Fig. 1, and by means of the spur-wheel K receives its motion from pinion L on the driving-shaft M. *g g* are the bearings of this shaft, and *h h* those for the shaft I.

The fly-wheel N is provided with a crank-handle *i* for working the machine by hand, while by means of pulley O the machine may receive its power through a belt.

The table B is provided with an oblong aperture, sufficiently large to allow the passing through of the largest size of envelopes, and on its top has two adjustable plates *l* and *l'*, (best seen in Fig. 4,) which may be set apart or closed to suit any-sized envelopes,

while for each size are provided smaller plates *m* and *m'* of the required width and length, so that these four plates, when properly adjusted, leave an aperture of the size of the envelope when folded.

The paper blanks are fed to the machine by the operator from a pile on the front of the table, their proper position being denoted by the small adjustable guides *k k*, (on the plate *l'*,) fitting into the corners formed by the two end flaps and one of the side flaps of the blank.

To the lower end of the sliding rod D is attached the T-shaped piece *n*, to which is again bolted a thin plate *o*, which corresponds in shape with the oblong aperture formed by the plates *l l'* and *m m'*, being, however, sufficiently smaller to pass through freely, while carrying with it the blank, with which it descends to the folding apparatus P. To regulate the termination of the downward movements of plate *o* to a nicely, the bolt-holes for securing the T-shaped piece *n* to rod D are made oblong, thus allowing the required adjustment. When the cam H during its revolving motion has raised the rod G sufficiently for the purpose, it leaves the roller *f*, whereupon the counter-balance *p* will weigh down again its end of lever F and bring it back into the position shown in the drawings.

The horizontal frame Q, which at its ends is bolted to the standards A and A', is provided with lugs *q q*, on which rests and is bolted the folder P. This folder is provided with two small compartments *r r*, Fig. 5, into which are led from the bottom the two branches of pipe *s*, the other end of which communicates with the cylinder R through the head *t*. Into this cylinder, which is secured to the back of frame Q, is fitted an airtight piston *t'*. A flat rod *u*, which at one end is screwed into this piston and at its other end works in the guide *v*, is provided with a small roller *v'*, Fig. 5, working on a stud *w*, Fig. 3, on a downward projection of the rod. By means of cam S actuating the roller *v'* a sliding motion in the direction of the arrow, Fig. 5, is imparted to the piston *t'*. The relative position of cam S on the shaft I to cam H is such that just before the arrival of the blank on the folder the piston *t'* will come into action. It will be easily seen that the

increase of space produced in the cylinder by the outward movement of the piston will create a partial vacuum in the cylinder, and consequently in the pipe and compartments of the folder, all communication with the atmosphere being shut off. The small holes x x , which lead from the top of the folder into the compartments r r , would be the only means for supplying air, but they being covered by the envelope while undergoing the process of folding cause the latter to act on the principle of valves and to be held down by the atmospheric pressure while the process of folding, hereinafter fully described, is going on. This being done and the cam S having released the roller v' , the piston t^2 will partly, by the pressure of the atmosphere on its exposed surface and by means of the spiral spring y , Fig. 3, regain its former position.

The two straps z z , which are bolted to the under side of table B and can be set closer or farther apart to suit different sizes of envelopes, serve to keep the end flaps turned up while the blank is descending, thereby causing a sufficient dragging on those flaps to prevent the blank from falling faster than the sliding rod D takes it.

The upright T , being bolted at the top to the horizontal frame Q , and secured at its lower end to another horizontal piece U , is provided with a dovetail slide a' , Fig. 2, on which works, by means of corresponding grooves at b' and b^2 , the sliding frame V . The round rods c' c^2 , which, similar to the upright T , are secured to frame Q and cross-piece U , serve as additional guides to the outer ends of sliding frame V , those ends being rounded and provided with holes of the required diameter to receive rods c' c^2 . To the rod c' is secured the stud d' , forming the fulcrum for lever W , which at one end is by means of link X connected to sliding frame V . The rod Z , which is jointed to the other arm of the lever and works in its guide e' , is depressed by the cam A^2 on the shaft I , thus causing the sliding frame V to rise, as shown at Fig. 2. When the cam has passed the rod Z , frame V will by its own weight descend to the position shown at Fig. 1, which motion is eased by the counter-balance B^2 .

f' f' f' f^2 are round pillars, resting with shoulders on the sliding frame V , to which they are secured by nuts. These pillars carry the lifters g' g' g' g^2 , which, on the ascent of sliding frame V , are brought in contact with pins or projections h' h' h' h^2 of the folding hinges i' i' i' i^2 . The radial movement of the hinges and their projections is such that when the lifter has elevated the latter sufficiently to bring the flats i' i^2 to bear on the surface of the folder P , as shown at Fig. 6, it is allowed to pass by and to ascend freely to the termination of its upward movement, while the hinges i' i^2 , by the overhanging weight of projections h' h^2 , are caused to fall back into their former position. The lifters g' g^2 are secured to the pillars by set-screws, which al-

lows them to be adjusted to give the one folder a sufficient precedence to the other to bring the flaps down in their proper order, and they are constructed with their tongues g^3 working on pins in such a manner that, coming in contact with the projections h' h^2 during the descent of sliding frame V , these tongues will by an upward radial movement clear those projections, whereupon their own weight will throw them back into their previous position.

At the back of the machine, on a level with shaft I , runs a shaft C' in its bearings D' D^2 , which receives motion from a pair of miter-wheels E' E^2 and revolves in the direction of its arrow, Fig. 2. It is provided with cam-arm F' , which actuates arm G' . This, with the curved arm H' , radiates in a bearing on the bracket I' , secured to the back of horizontal frame Q . The main portion of the curved arm H' forms a segment of a circle struck from the center of vibration and works in a slot k' , Fig. 3, through the folder P . The function of this lever is to remove the finished envelopes from the folder. This it performs by raising them suddenly on the depression of arm G' , which causes it to radiate in the direction of its arrow, Fig. 2, and to land the envelopes on the inclined table K' , Fig. 2, from where they will slide either on a table or some other suitable place for counting and packing them. To give room for the above discharging apparatus, the pillar f^2 is not, like the others, on a line with the center of its respective folding hinge, but placed on one side, as shown at Fig. 3, the projections h^2 on folding hinge i^2 being provided with a long pin, which extends toward pillar f^2 and on the end of which acts the lifter g^2 . The pillars f' f^2 , being secured to sliding frame V through slots, can therefore be moved and adjusted to suit any required sized folder, which folders, as will be easily seen, may vary from the smallest to the largest desirable size by only adhering to the same distances for the holes through which the holding-down bolts pass, and keeping the same dimensions for the openings, through which the ends of pipe s are introduced, these ends fitting with a slight taper and requiring no further adjustment.

Before the blank is removed from the table B to the folder P the paste is applied to it by two small oblong vessels l^2 l^2 , quite narrow at the bottom, where, in case of stiff flour paste being used, they may be quite open, while when gum-arabic is made use of they may have a strip of sponge inserted, which must be so pressed in to be always sufficiently damp for the purpose, without allowing more to flow off than required. These vessels are secured to an adjustable arm L' on the lever M' , which has its fulcrum in the small stand m^2 and receives motion through the rod n' from cam N' on the shaft C' . The lower end of rod n' is provided with a slot, through which passes the shaft C' , thus serving as a

guide for the up and down movements of the rod. Cam N' , by pressing down the roller o' on the rod n' , retains it and the lever M' in the position shown at Fig. 2 until its point p' passes roller o' , thus allowing it to rise sufficiently to let the bottom of vessels $b^2 b^3$ touch the blank, the vessels being raised again as the gradual rise on the cam N' depresses the roller o' . The holes through which arm L' is bolted to lever M' are oblong, which allows the vessels $b^2 b^3$ to be adjusted to the different-sized blanks. Opposite these vessels (on the front part of table B) is placed the swivel-bearing O' of the stamp P' , which stamp works in the fulcrum y' , and at one end is provided with the dice p' for producing the desired ornament on the seal-flap of the envelope, while the other arm receives motion from a cam Q' by means of pin r' , which plays in a hole through the center of the vertical axis of swivel O' . The cam Q' works on a pin between the brackets $R' R'$, and derives its motion from another cam T' on the main shaft I by means of rod S' , which at one end connects to arm s' on cam Q' , while its other end is formed into an oblong slot which guides it on the shaft I. Its downward projection t' , Fig. 1, is provided with the roller u' , which, on being actuated by cam T' , causes rod S' to move in the direction of its arrow, Fig. 1, thereby forcing up the pin r' , and consequently depressing the dice p' on stamp P' . When the desired effect is produced and the cam T' has released the roller u' on the rod S' , the spring v' , Fig. 1, by its pressure against the under side of stamp P' , causes the stamp and its movers to come back into the position shown at Fig. 1. To prevent the stamp P' from becoming an obstacle to the feeding of the blanks, its bearing is made to swivel on its axis in the perpendicular journal U' , bolted to the lower side of table B and partly projecting up through an oblong hole w' , Fig. 2. The bolts $x' x'$ for securing this journal pass through slotted holes in the plate B and tap into the flanges on the journal U' , which by this means may be adjusted to suit the different-sized blanks, the face of cam Q' being wide enough to produce the same action on pin r' in any of the required positions.

To the lower end of swivel-bearing O' is attached the arm y' , which joints to the rod z' , the other end of which is again connected to lever 1. This lever has its fulcrum at 2, below which extends its short arm 3. This short arm is caused to bear against the face of cam 4 on the shaft I by the spiral spring 5 pulling on rod z' in the direction of its arrow, Fig. 1, and during the greatest part of a revolution of cam 4 retains the stamp P' in the position shown at Fig. 1.

The offset on the cam 4 allows the short arm 3 to move in the direction imparted to it by the spiral spring 5, when the stamp P' will swivel on its axis to the position shown at Fig. 4, and there remain till the blank is stamped, as before described, whereupon the

cam 4 acts again on the short arm 3 of lever 1, and the stamp is again brought into the position shown at Fig. 1, which, as will be easily seen, greatly facilitates the feeding of the blanks.

Operation: The downward stroke of the rod D being completed during less than one-fourth of the whole revolution of shaft I, and its ascent being almost instantaneous, three-fourths of the time required for each operation is allowed for the feeding of the blank. The relative position of the various cams is such that cam 4 and cam T' on the shaft I and cam N' on the shaft C' come into action just soon enough before the descent of rod D to have completed the stamping and pasting, when the cam II on the shaft I, by its action on rod G, causes sliding rod D, with its plate o, to descend, whereby the blank is removed from the table through the aperture formed by the plates $l' l'$ and $m' m'$ to the folder P. Just then the cam S comes into action, and by causing the piston t^2 to move in the direction of its arrow, Fig. 5, produces a partial vacuum in the cylinder R, the pipe s, and compartments $r' r$ of the folder P. The small holes $x' x'$, which pass from the top of the folder into the compartments $r' r$, and which are the only inlets for air, are now covered by the blank, which, therefore, by the atmospheric pressure from above, is held firm during the operation of folding. This is performed directly after rod D has ascended by the cam A^2 on the shaft I, which, depressing the rod z, elevates sliding frame V with its pillars $f' f^2$. These, with their lifters $g' g^2$, actuate the folding hinges $i' i^2$ in the above-described manner. As soon as the folding is completed the cam F' on the shaft C' is caused to come in contact with arm G', which, being suddenly depressed, rotates arm II' in an upward direction through slot K' in the folder P, lifting with it the completed envelope and landing it on the inclined table K'. The next blank, which the operator has fed in the meantime, again undergoes the various treatments in the described order.

Having now described the nature of my invention, I wish it to be understood that I am well aware that jets of compressed air have been used to assist in folding envelopes, as is the case in the machine of M. Rémond, which is unlike my invention. I also do not claim the folding hinges exclusively, a similar device having been used heretofore.

I am also now aware that atmospheric pressure is claimed for holding the blank during the operation of folding in William H. Lowe's patent, April 8, 1856, which I disclaim; but

What I do claim, and desire to secure by Letters Patent, is—

1. Giving the sliding rod D a downward movement by means of link E, lever F, rod G, and cam II, in the manner and for the purpose set forth.

2. Giving a sliding movement to the frame V by means of link X, lever W, rod Z, and

cam A', thereby operating, by means of lifters g' g' g' g², the folding hinges i' i' i' i², in the manner described.

3. The compartments r r, in combination with pipe s and cylinder R, the latter being provided with piston l², which is operated by cam S on shaft I, the whole being constructed substantially in the manner set forth.

4. The stamp P', working in the swivel-bearing O' and operated by cam Q', pin r', rod S', and cam T', in the manner and for the purpose specified.

5. The employment of cam 4, lever 1, rod Z', arm y', and spiral spring 5, to turn swivel-

bearing O' on its axis, substantially in the manner and for the purpose set forth.

6. Operating the pasting-vessels l² l² by the lever M', rod n', and cam N', substantially as described.

7. Applying the curved arm H', working in a slot k' through the folder P, for removing the finished envelopes to the inclined table K' and operating it by arm G' and cam-arm F', as shown.

THEODORE BERGNER.
